METHOD AND APPARATUS FOR MAKING
FINNED TUBES

Ray C. Edwards, Glen Rock, N. J.

Application August 8, 1949; Serial No. 109,085

8 Claims. (Cl. 29—157.3)

1

The invention herein disclosed relates to machines for making radiator, condenser, or convector tubes which have extended surfaces made up of a strip or ribbon of thin material, preferably sheet metal wound spirally around the tube. The primary object is to provide a machine which is compact in form and into which a tube is fed and rotated in such a manner that a plurality of thin strips of material, preferably metal, may be helically wound around the tube and secured thereon all in one operation. Prior to this time it had been customary to apply only one thin strip of ribbon at one time.

By helically wrapping two or more fins simultaneously about the tube a number of important objectives and advantages are realized:

First, the production rate of the finning machine is increased in proportion to the number of fins applied simultaneously.

Secondly, an equally important object of this machine is to include a slitting device as part of the machine mechanism. With a means for slitting it is possible to utilize low cost wide fin strip and slit the strip as it is fed into the machine. Narrow finned strip is costly.

Thirdly, by slitting the strip as it is fed to the finning machine the difficulties encountered in handling a narrow thin strip are eliminated.

In the drawings:

Figure 1 is an isometric view of the complete 30 slitting, crimping, finning and synchronizing mechanism.

Figure 2 is a side view of the slitting rollers.

Figure 3 is a top view of the slitting rollers.

Figure 4 is a side view of the finned tube.

Figure 5 is an end view of the finned tube.

Figure 6 is a side elevation of the mechanism used to apply the fin strip to the tube.

Figure 7 is a top view of the mechanism used to apply the fin strip to the tube.

On Figure 1 of the drawing, 1 illustrates the wide initial strip, preferably of metal, from which the fins are formed. It was found advisable to purchase the strip in widths greater than $\frac{1}{4}$ ". Strips with widths greater than $\frac{1}{4}$ " may be purchased for as much as 25% less per pound than narrower strips. Also, most suppliers are very reluctant to take the responsibility of slitting and reeling the narrow strips. For the condensation of refrigerant vapors, particularly the organic refrigerants, fins $\frac{1}{8}$ " wide are preferred. However, the purchase of such narrow strip is impractical, as the strips snarl severely when wound on reels in preparation for shipment.

The strip 1 passes between the slitting rollers 55 and into the crimping mechanism 41. Within the crimping mechanism the strip is crimped and wound spirally around the tube 10.

2 driven by a belt drive. Power for driving the slitting rollers is obtained directly from the transmission 3 or from the shaft driving the crimping gears 4. The slitting rollers 2 are of conventional design and basically consist of hardened steel ground discs having a thickness corresponding to the width of the slit strip. The slitting rollers are of two diameters and are alternated on their driving shafts so that they will mesh and slit the strip as it passes between them.

After slitting, the component strands pass around a pin 5. The pin divides the strip into the number of strands into which the strip has been slit and the pin 5 assures that the strip has been separated into its component strands.

After the component strips pass pin 5 the strands pass around idler pulley 6 and thence to the crimping mechanism. The purpose of idler pulley 6 is to tension the strands after they leave the slitter, and also to synchronize the operation of the crimping and slitter. If the strands of strip leave the slitter more rapidly than they pass through the crimping 41, idler pulley 6 drops and by means of the synchronizing link 51 the slitting operation is retarded, until the slitting and crimping take place at a simultaneous rate, or until the two operations are synchronized.

The synchronizing is accomplished by the following procedure:

If the slitting rollers feed the slit strip too rapidly, idler pulley 6 drops, this in turn raises idler pulley 7. When idler pulley 7 raises, the belt 9 moves outward radially on the spring loaded synchronizing pulley 8, thereby increasing the operating diameter of synchronizing pulley 8. When the operating diameter of 8 increases, the rotative speed of the slitting cutters, which are mounted on the same shaft as the synchronizing pulley 8, is slowed down with respect to the shaft 10, upon which the crimping gears 4 are mounted.

The opposite sequence of events occurs if idler pulley 6 is caused to rise. In that event the slitting cutters are driven more rapidly with respect to the crimping gears.

In some instances it might not be desirable to employ the use of crimping gears. In that case the plurality of strips can be fed directly to the tube and simultaneously wound on the tube without the crimp. Also, if the crimping operation is eliminated, the slitting cutters could be driven by the transmission 3 rather than by the shaft 4 upon which one of the crimping gears is mounted.

After passing over idler pulley 11, the slit strips 55 pass into the crimping 41. Within the crimping mechanism the strip is crimped and wound spirally around the tube 10.

strips may be crimped transversely for their entire width or only along one edge. After leaving the crimping gears, the strips pass down around idler pulley 12 and thence upward to the strip comb 13 which guides the strip which may or may not be crimped to the ironing rollers 16. The tube 15 upon which the strips are thereby wound is positioned with respect to the comb and the ironing roller in a manner shown in Figure 6. Tube 15 is rotated and longitudinally advanced by a suitable set of gears and rollers which are not shown and are located in the transmission. The operation of the crimping mechanism is synchronized with the rotation of the tube by the same type of mechanism used to synchronize the slitting and the crimping operation.

An excess of crimped strip will lower the position of idler 12, which in turn raises the position of idler 19, which causes the spring loaded synchronizing pulley 20 to increase its effective pitch diameter. Increasing the pitch diameter of synchronizing pulley 20 slows the operation of this pulley down with respect to the rotation of speed of the transmission 3, and thus correspondingly the crimping gears which are mounted on the same shaft. If idler pulley 12 is caused to rise for any reason the opposite sequence of events will occur. As the tube 15 in its rotational and translational motion leaves the ironing roller 16 the finned tube is then subjected to a spray 17 of soldering flux. After leaving the flux spray the tube transversely moves into a spray of molten solder 18 and there the applied fin of the multiple pitch is bonded to the tube.

All of the operations herein described operate simultaneously and no other care is required by the operator than the replacement of strip and tube as it is used by the machine.

What I claim is the following:

1. The method of applying thin narrow radiation fins on a tube, which consists in splitting a relatively wide strip of thin metal into a plurality of uniform narrow strips, passing the thin narrow strips simultaneously through crimping means for laterally crimping them, simultaneously winding the thin narrow strips in uniform spaced parallel relation edgewise upon a tube, applying soldering flux to the strips wound upon the tube, subjecting the tube and strips to a soldering bath for coating and securing the strips to the tube, and synchronizing the feeding of the wide strip during the splitting operation with the crimping and winding operations of the narrow strips.

2. The method of applying thin narrow fins on a tube which consists in continuously moving a fin forming metal strip from a source of supply until the fins are applied to a tube and during said continuous movement splitting the metal strip into a plurality of uniform narrow strips, simultaneously crimping the narrow strips laterally of their length, maintaining the narrow strips in approximate edgewise alignment during the crimping operation, guiding the narrow strips into parallel relationship and simultaneously winding the parallel narrow strips edgewise in uniform spaced relation upon a tube.

3. The method of applying thin narrow fins on a tube which consists in continuously moving a fin-forming metal strip from a source of supply until the fins are applied to a tube and during said continuous movement splitting the metal strip into a plurality of uniform narrow strips, simultaneously crimping the narrow strips laterally of their length, maintaining the narrow

strips in approximate edgewise alignment during the crimping operation, guiding the narrow strips into parallel relationship and simultaneously winding the parallel narrow strips edgewise in uniform spaced relation upon a tube, applying soldering flux to the strips wound upon the tube, subjecting the tube and strips to a soldering bath for coating and securing the strips to the tube, and synchronizing the feeding of the wide strip during the splitting operation with the crimping and winding operations of the narrow strips.

4. The method of applying thin narrow fins on a tube which consists in continuously moving a fin-forming metal strip from a source of supply until the fins are applied to a tube and during said continuous movement splitting the metal strip into a plurality of uniform narrow strips in approximately edgewise alignment, guiding the narrow strips from edgewise alignment into parallel relationship, simultaneously winding the parallel narrow strips edgewise in uniform spaced relation edgewise upon a tube, applying soldering flux to the strips wound upon the tube, and subjecting the tube and strips to a soldering bath for coating and securing the strips to the tube.

5. In a machine for making finned tubes, the combination of, means for revolving and moving longitudinally a tube to be finned, slitting means for slitting a metallic strip into a plurality of individual fin-forming strips, crimping rollers for simultaneously crimping said strips, means for driving said crimping rollers, means connecting said crimping roller driving means to said tube revolving and moving means to provide synchronous operation of said crimping rollers and said tube revolving means, means for driving said slitting means, power transmission means connecting the driving means of said slitting means and the driving means of said crimping rollers

40 to provide synchronized operation of the splitting means and crimping rollers, a strip guiding comb supported adjacent to said tube to be finned and receiving said strips from said crimping rollers, said comb acting to guide said fin-forming strips into spaced parallel relationship with each other, and an ironing roller mounted adjacent to said comb and tube and receiving the fin-forming strips from said comb to deform and wind the strips in parallel edgewise relation about and in contact with the tube, means for driving said ironing roller, and means to provide synchronized operation of said ironing roller driving means and said tube revolving means.

6. In a machine for making finned tubes, the combination of, means for revolving and moving longitudinally a tube to be finned, slitting means for slitting a metallic ribbon into a plurality of individual fin-forming strips, means for driving said slitting means, power transmission means connecting the driving means of said slitting means and said tube revolving and moving means to provide synchronous operation of the slitting means and the tube revolving and moving means, means for deforming and winding the fin-forming strips in uniform parallel edgewise relation about and in contact with the tube, means for driving said fin-forming strip deforming and winding means, and means to provide synchronized operation of said strip deforming and winding means and said tube revolving means.

7. In a machine for making finned tubes, the combination of, means for revolving and moving longitudinally a tube to be finned, slitting means for slitting a metallic ribbon into a plurality of individual fin-forming strips, means for driving

said slitting means, power transmission means connecting the driving means of said slitting means and said tube revolving and moving means to provide synchronous operation of the slitting means and the tube revolving and moving means, a strip guiding comb supported adjacent to the tube to be finned and engaging said tube forming strips, an ironing roller mounted adjacent said comb and tube and receiving the fin-forming strips from said comb to deform and wind the strips in uniform parallel edgewise relation about and in contact with the tube, means for driving said ironing roller and means to provide synchronized operation of said ironing roller driving means and said tube revolving means.

8. In a machine for making finned tubes, the combination of, means for revolving and moving longitudinally a tube to be finned, slitting means for slitting a metallic ribbon into a plurality of individual fin-forming strips, crimping rollers for simultaneously crimping said strips, means for driving said crimping rollers, means connecting said crimping roller driving means to said tube revolving and moving means to provide synchronous operation of said crimping rollers and said tube revolving and moving means, means for driving said slitting means, power transmission means connecting the driving means of said slitting means and the driving means of said crimping rollers to provide synchronized opera- 30

5

tion of the slitting means and crimping rollers, an ironing roller mounted adjacent to said tube for deforming and winding the fin-forming strips in uniform parallel edgewise relation about and in contact with the tube, means for driving said ironing roller, and means to provide synchronous operation of said ironing roller driving means and said tube revolving means.
